[57] CLAIM

The ornamental design for a protective sheath cover for a hypodermic syringe needle, substantially as shown and described.

DESCRIPTION

FIG. 1 is a front elevational view of a protective sheath cover for a hypodermic syringe needle showing our new design;

FIG. 2 is a rear elevational view thereof;

FIG. 3 is a side elevational view thereof;

FIG. 4 is a front perspective view thereof; and

FIG. 5 is a rear perspective view thereof.

FIG. 1.

FIG. 2.

FIG. 4.

FIG. 5.
